ELMER S. SMITH, OF BOUND BROOK, NEW JERSEY, ASSIGNOR, BY MESNE ASSIGNMENTS, TO INTERNATIONAL ACCESSORIES MANUFACTURING COMPANY, OF WILMINGTON, DELAWARE, A CORPORATION OF DELAWARE.

CARBURETER.

1,074,577.

Specification of Letters Patent. Patented Sept. 30, 1913.

Application filed May 22, 1909. Serial No. 487,646.

To all whom it may concern:

Be it known that I, ELMER S. SMITH, a citizen of the United States, and a resident of Boundbrook, in the county of Somerset and State of New Jersey, have invented certain new and useful Improvements in Carbureters, of which the following is a specification.

The invention relates to improvements in carbureters for hydrocarbon engines, and it consists in the novel features, arrangements and combinations of parts hereinafter described, and particularly pointed out in the claims.

15 The object of my invention is to provide a simple and highly efficient carbureter for automatically supplying gas of the requisite quality, in accordance with the work demanded, to the cylinder of the engine 20 with which the carbureter may be connected. I contemplate the use of my carbureter in connection with the cylinders of automobile engines for supplying the gas thereto. The 25 quantity and quality of gas supplied to automobile cylinders should vary in accordance with the demands of the engine, and the quantity of the gasoline supplied to air on the suction strokes of the piston or pistons, should be capable of automatic regulation as well as of predetermined adjustment, and to accomplish these objects are 30 among the purposes of my invention.

The carbureter apparatus of my invention comprises a reservoir or tank within which 35 a uniform level of gasoline is maintained, a casing connected with the conducting pipe leading to the cylinder of the engine, and a cylindrical receptacle pivotally mounted within said casing and in communication 40 with the gasoline and formed with a wing valve for controlling the air supply through the pipe and also with a series of radial outlet nozzles or small pipes for gasoline, said nozzles defining in their connection with 45 said receptacle an inclined or spiral line extending along about one-quarter of the circumference of the receptacle. The receptacle carrying said wing valve and series of outlet nozzles is mounted to rock or oscillate on its 50 longitudinal axis under fluctuations of air pressure, and to deliver more or less of the gasoline to said nozzles in accordance with

its position, said nozzles being normally above the level of the liquid in the receptacle and having their lower ends carried 55 below such level as the receptacle is more or less turned on its horizontal axis. Under a light stroke of the piston only a very few of the inner ends of the nozzles will be carried, by the turning of the receptacle, to a 60 position to receive gasoline, while under a stronger suction stroke of the piston an additional number of said nozzles will have their lower ends carried downwardly to a 65 sufficient extent to receive the gasoline, and hence the feed of the gasoline, as well as of the air, will depend upon the nature of the 70 strokes of the piston, and said strokes will be, as usual, in accordance with the demands on the engine or the work to be performed. 75 My invention enables a sensitive control of the gas supplied in accordance with the requirements of the engine, and the richness of the gas being proportioned to such demands. I also provide means for manually 80 turning said receptacle, as occasion may require, so that, for example, if the automobile should be descending a hill all of the outlet nozzles may be carried above the level of the gasoline, or if ascending a steep hill 85 all of said nozzles could be carried downwardly to receive the gasoline.

The invention will be fully understood from the detailed description hereinafter presented, reference being had to the accompanying drawings, in which:

Figure 1 is a central vertical longitudinal section of a carbureter constructed in accordance with and embodying the invention; Fig. 2 is a horizontal section through a portion of the same on the dotted line 2—2 of Fig. 1; Fig. 3 is a vertical transverse section, through a portion of the same, on the dotted line 3—3 of Fig. 1; Fig. 4 is a vertical transverse section on the dotted line 4—4 of Fig. 1 of a spring-and-lever mechanism connected with the cylindrical receptacle located within the air and gas conduit or chamber; and Fig. 5 is a like section through a portion of the same on the dotted line 5—5 of Fig. 1.

In the drawings, 10 designates a tank or reservoir for the gasoline, and 11 a casing forming within it a mixing chamber for

the air and vapor, and connected, as usual, by a pipe, not shown, with the cylinder of the engine.

The tank 10 contains a float 12 and is provided with a supply pipe 13 whose inlet to the tank 10 is controlled by a suitable valve 14 operably connected with the float 12 so that the latter when tilting downwardly at one side of its support may open said valve to admit an additional supply of gasoline to the tank and when tilted upwardly at said side, due to the rise of gasoline in the tank, may close said valve and cut off any further supply, for the time being, of gasoline to the tank. The float 12 serves in connection with the gasoline in the tank 10 to automatically control the valve 14 and maintain a predetermined level of gasoline within the tank.

Within the cylindrical casing 11 is mounted a horizontal cylindrical rotary tube or receptacle 15 which extends transversely within said casing and at one end is mounted on a shaft or stem 16 which extends through one side of the casing 11 and at the other end on a hollow hub 17 which extends through the other side of said casing 11 and projects within a hollow pipe-union 18 which connects the tank 10 with said receptacle 15. The horizontal center line of the receptacle 15 is nearly on a level with the normal level of gasoline in the tank 10, and hence normally the gasoline uninterruptedly flows from the tank 10 into the receptacle 15 until the predetermined level of the gasoline has been attained and the supply cut off by the float 12 and valve 14. I preferably provide free passage for the gasoline to the receptacle 15, but furnish means for controlling the communication from the tank 10 to the receptacle 15 so that whenever desired the flow of the gasoline into the receptacle 15 may be restricted or entirely cut off, such means in the present instance being a valve 19 extending through the shaft or stem 16 and receptacle 15 and adapted at its inner end to a conical valve seat formed in the hub 17 surrounding the opening therein. The valve stem is threaded and engages a threaded opening in the shaft 16, and said stem 19 is provided on its outer end with a suitable head 20 by which it may be readily turned in one direction or the other. The hub 17 will preferably be packed by means of a gland 21, and during the rotary movement of the receptacle 15 the hub 17 may turn with said receptacle in its bearing aperture provided in the side of the section 11. The shaft or stem 16 supporting the opposite end of the receptacle 15 is adapted to have a rotary movement in the bearing aperture provided for it in the side of the pipe section 11. I also preferably provide an elbow 9 on the hub 17 with its vertical arm nor-

mally turned downwardly into the gasoline in the tank 10, said arm being of sufficient length to always have its lower end remain submerged in the gasoline during any tilting of the automobile and also during usual oscillations of the receptacle 15.

The receptacle 15, with its connected parts, constitutes one of the more important features of the invention, and said receptacle extends entirely across the mixing chamber within the casing 11 and at its opposite sides is formed with wings 22, 23 constituting a valve and at its upper side above said wings is equipped with a series of radial nozzles or small pipes 24, these pipes 24 all being of about the same length and disposed on an inclined line extending throughout about one-quarter of the circumference of the receptacle 15. The pipes 24 are suitably spaced apart and occupy the middle portions of the mixing chamber above the receptacle 15, and the inner ends of said pipes due to their inclined or spiral arrangement, are on varying levels above the gasoline in said receptacle, as shown in Fig. 1, in which the left hand pipe 24 is shown as vertical with its inner end at the maximum point above the level of the gasoline, while the second to the left hand pipe has its inner end on a slightly lower level than the left hand pipe, and the other pipes in series extending toward the right have their inner ends on gradually lower levels until the right hand pipe is reached with its inner end almost on a level with the gasoline. I vary the locations of the inner ends of the pipes 24 in the manner indicated, so that when the receptacle is only slightly turned from its initial position, only one or more of the pipes 24 shall receive gasoline, and when a somewhat greater turn is given to the receptacle 15 an added number of the pipes 24 may receive gasoline, and so on in accordance with the action of the piston in creating the suction which turns said receptacle or the necessities of the engine. I preferably provide each of the pipes 24 at its outer end with a contracted opening and a needle valve 25 therefor, so that the outlet from the pipes 24 may be given a predetermined size in accordance with the conditions that may be met in actual service.

The wings 22, 23 are preferably cast integrally with the receptacle 15 and define, with the adjacent portions of the receptacle, a disk closing, when in a horizontal position, the mixing chamber, with the exception of a passage 26 left by the formation of a recess 27 in the edge of the wing 22. I provide the recess 27 in the wing 22 so that at no time shall the air passage be entirely closed. The wing 23 differs from the wing 22 in that its edge is not provided with a recess 27 and it carries a lower section 28

which is in the form of a quarter of a sphere conforming to the inner adjacent walls of the mixing chamber and adapted during the ordinary oscillatory rotations of the receptacle 15 to substantially exclude air from passing between it and the adjacent wall of said chamber, my purpose being that the air passing upwardly by the receptacle 15, shall enter by passing between the outer edge of the wing 22 and the adjacent wall of said chamber. I provide the quarter-spherical section 28 on that quarter of the surface of the receptacle 15 which is diagonally opposite to that portion of said surface which carries the series of pipes 24, said pipes and said section 28 being so proportioned that, as nearly as may be, there will be a natural balancing of the receptacle 15 with the wings 22, 23 horizontal. During the suction stroke of the piston, the vacuum action will tilt the wing 23 upwardly and allow the wing 22 to correspondingly descend, the suction being greater against the wing 23 by reason of its not having a portion of its surface cut away. I, however, provide a spring 29 on the stem or shaft 16 for normally maintaining the receptacle 15 with its parts in the initial position in which the same is shown in Figs. 1 and 2. The spring 29 is a coiled spring connected at its inner end to the shaft and at its outer end to a lever 30 free on the shaft 16. The spring 29 is so tensioned as to normally hold the wings 22, 23 horizontal and when during the operation of the engine the wings are tilted to admit air through the mixing chamber, the spring 29 will be placed under a tension normally acting to restore said wings to their horizontal position. At any time it may be desired to turn the receptacle 15 and wings 22, 23 manually as when it may be desired to suddenly obtain a greatly increased supply of gasoline or to cut off such supply the operator, according to usual methods, will, through a connecting rod 31 and the aforesaid lever 30, turn the shaft 16 to move the wings 22, 23 and with them the outlet pipes 24 to the required position. The casing 11 is provided with stop pins 32 and the shaft 16 with a projecting pin 33 to engage the pins 32 during the movement of the receptacle 15 and thus prevent said receptacle from being given an undue movement on its axis.

The operation of the carbureter will be largely understood from the foregoing description without further detailed explanation. As the receptacle 15 is turned either under the action of the suction stroke of the piston or manually by the operator, a greater or less number of the pipes or nozzles 24 will pass below or above the level of the gasoline, and hence the quantity of gasoline issuing from said pipes or nozzles will vary with conditions and requirements, the result

being that the quality of the gas will vary, the leaner gas being supplied for light work and the richer gas when the demand on the engine is greater. The position of the wings 22, 23 controls the air supply through the casing 11, and the construction and arrangement is such that with an increased supply of air, when the engine is doing a heavy duty, a greater number of the nozzles or pipes 24 will deliver gasoline. When an automobile employing the invention is climbing a steep hill, the receptacle 15 may be turned toward the right (looking at Fig. 3) so as to carry a greater number of the pipes or nozzles 24 downwardly to receive and deliver gasoline, and also to open the valve more widely for the purpose of admitting sufficient air. When the automobile is descending a hill and not requiring any special amount of gas, the receptacle 15 may be manually turned toward the left (looking at Fig. 3) so as to carry all of the pipes or nozzles 24 upwardly entirely clear of the gasoline within said receptacle, in which position the valve wing 23 at the other side of said receptacle is depressed below the horizontal, and air is allowed to pass the wings on both sides unmixed with gasoline to the center. To enable this, the curved shield or quartered sphere 28 is not carried above the level of the wing 23.

I illustrate the receptacle 15 as provided with seven of the pipes or nozzles 24, but a greater or less number of these pipes or nozzles may be employed in accordance with the size of the apparatus and the work to be performed. One advantage in having a surplus number of the pipes or nozzles 24 is that some of these pipes or nozzles may be closed at their outer ends and held in reserve for use should the other nozzles become foul or inoperative when the automobile is in actual service.

What I claim as my invention and desire to secure by Letters-Patent, is:

1. In combination with a casing having an air inlet and a mixture outlet, a combined valve and fuel receptacle disposed across said casing, having its normally horizontal dimensions approximately corresponding to the internal horizontal cross section of said casing and of less vertical than horizontal dimension, and having the wall of the fuel receptacle apertured to discharge fuel therefrom, whereby the fuel discharge and air passage are correspondingly increased as the combined valve and fuel receptacle is rotated.

2. In combination with a casing having an air inlet and a mixture outlet, a rotatable member comprising a fuel receptacle disposed across said casing to act as a valve approximately closing the passage therethrough when in normal position, the wall of the fuel receptacle being apertured to per-

- mit the discharge of fuel in amounts dependent upon the amount of rotation of said member, and means for rotating the said member to elevate the fuel discharging means and prevent the discharge of fuel while permitting air unmixed with fuel to pass.
3. A carbureter having a chamber for the passage of the air and gasoline, a transverse rotary receptacle therein, a source of gasoline supply connected with said receptacle, a series of outlets connected at their inner ends with the interior of said receptacle at different heights, whereby as said receptacle is rotated said outlets are successively moved to or from their discharging position and a variable discharge of the gasoline is secured, and means for rotating said receptacle.
- 10 4. A carbureter having a chamber for the passage of the air and gasoline, a transverse rotary receptacle therein, a source of gasoline supply connected with said receptacle, a series of outlets connected at their inner ends with the interior of said receptacle at different heights, whereby as said receptacle is rotated said outlets are successively moved to or from their discharging position and a variable discharge of the gasoline is secured, and means for rotating said receptacle, said outlets having independent control valves.
- 15 5. A carbureter having a chamber for the passage of the air and gasoline, a transverse rotary receptacle therein, a source of gasoline supply connected with said receptacle, a series of outlets connected at their inner ends with the interior of said receptacle at different heights, whereby as said receptacle is rotated said outlets are successively moved to or from their discharging position and a variable discharge of the gasoline is secured, and means for rotating said receptacle, said outlets being arranged
- 20 45 on a line extending partly around the upper side of said receptacle.
6. A carbureter having a chamber for the passage of the air and gasoline, a transverse rotary receptacle therein, a source of gasoline supply connected with said receptacle, a series of outlets connected at their inner ends with the interior of said receptacle at different heights, whereby as said tube is rotated said outlets are successively moved to or from their discharging position and a variable discharge of the gasoline is secured, a valve for controlling the passage through said chamber and connected with said receptacle for simultaneous operation therewith, and means for operating said valve and receptacle.
- 25 7. A carbureter having a chamber for the passage of the air and gasoline, a transverse rotary receptacle therein, a source of gasoline supply connected with said receptacle,

a series of outlets connected at their inner ends with the interior of said receptacle at different heights, whereby as said receptacle is rotated said outlets are successively moved to or from their discharging position and a variable discharge of the gasoline is secured, a valve for controlling the passage through said chamber and connected with said receptacle for simultaneous operation therewith, means normally yieldingly maintaining said receptacle in its initial position, and means for manually rotating said receptacle and valve.

8. A carbureter having a cylindrical chamber therein for the passage of the air and gasoline, a transverse rotary receptacle in said chamber having valve wings at opposite sides thereof, a source of gasoline supply connected with said receptacle, a series of outlets connected with the interior of said receptacle at different heights, whereby as said receptacle is rotated said outlets are successively moved to or from their discharging position and a variable discharge of the gasoline is secured, and means for rotating said receptacle, one of said valve wings having a shield section depending therefrom to exclude the passage of air along its side of said chamber.

9. A carbureter having a chamber for the passage of air and gasoline, a transverse rotary receptacle in said chamber having at its upper side a series of discharge outlets, a source of gasoline supply connected with said receptacle, a valve for controlling the passage through said chamber and connected with said receptacle for simultaneous operation therewith, and means for operating said receptacle and valve.

10. A carbureter having a chamber for the passage of air and gasoline, a transverse rotary receptacle in said chamber having at its upper portion a series of discharge outlets, a valve operating therewith a source of gasoline supply connected with said receptacle, and means for operating said receptacle and valve.

11. In a carbureter of the character described, the combination with an outer shell having an air inlet and a mixture outlet, a fuel receptacle pivotally disposed in said shell, said receptacle in normal position substantially closing the air passage between said inlet and said outlet, said receptacle having a plurality of fuel passages in its wall disposed at different distances above the fuel level in said receptacle and adapted to consecutively come into action to supply fuel into said outer shell when said receptacle is tilted and the air passage between said inlet and outlet is gradually opened, the number of active fuel passages increasing with the size of the air passage.

12. A carbureter having a chamber for the passage of the air and gasoline, a trans-

- verse rotary tube therein, a source of gasoline-supply connected with said tube, a series of radial outlet pipes connected at their inner ends with said tube at different heights, whereby as said tube is rotated said pipes are successively moved to or from their discharging position and a variable discharge of the gasoline is secured, and means for rotating said tube.
13. A carbureter having a chamber for the passage of the air and gasoline, a transverse rotary tube therein, a source of gasoline-supply connected with said tube, a series of radial outlet pipes connected at their inner ends with said tube at different heights, whereby as said tube is rotated said pipes are successively moved to or from their discharging position and a variable discharge of the gasoline is secured, and means for rotating said tube, and independent control valves in said pipes.
14. A carbureter having a chamber for the passage of the air and gasoline, a transverse rotary tube therein, a source of gasoline-supply connected with said tube, a series of radial outlet pipes connected at their inner ends with said tube at different heights, whereby as said tube is rotated said pipes are successively moved to or from their discharging position and a variable discharge of the gasoline is secured, and means for rotating said tube, said pipes being arranged on a line extending partly around the upper side of said tube.
15. A carbureter having a chamber for the passage of the air and gasoline, a transverse rotary tube therein, a source of gasoline-supply connected with said tube, a series of radial outlet pipes connected at their inner ends with said tube at different heights, whereby as said tube is rotated said pipes are successively moved to or from their discharging position and a variable discharge of the gasoline is secured, a valve for controlling the passage through said chamber and connected with said tube for simultaneous operation therewith, and means for operating said tube and valve.
16. A carbureter having a chamber for the passage of the air and gasoline, a transverse rotary tube therein, a source of gasoline-supply connected with said tube, a series of radial outlet pipes connected at their inner ends with said tube at different heights, whereby as said tube is rotated said pipes are successively moved to or from their discharging position and a variable discharge of the gasoline is secured, a fan-valve for controlling the passage through said chamber and having its wings at opposite sides of and connected with said tube, and means for operating said valve and tube.
17. A carbureter having a chamber for the passage of air and explosive mixture and a combined fuel containing and feeding re-
- ceptacle and air valve, effecting the variation of both fuel and air passing through said chamber and means for rotating said valve.
18. A carbureter having a cylindrical chamber therein for the passage of the air and gasoline, a transverse rotary tube in said chamber having valve wings at opposite sides thereof, a source of gasoline-supply connected with said tube, a series of radial outlet pipes connected with said tube at different heights, whereby as said tube is rotated said pipes are successively moved to or from their discharging position and a variable discharge of the gasoline is secured, and means for rotating said tube, one of said valve-wings having a quarter-spherical section depending therefrom to exclude the passage of air along its side of said chamber.
19. A carbureter having a chamber for the passage of air and gasoline, a transverse rotary tube in said chamber having at its upper side a series of discharge outlets, a source of gasoline-supply connected with said tube, a valve for controlling the passage through said chamber and connected with said tube for simultaneous operation therewith, and means for operating said tube and valve.
20. A carbureter having a chamber for the passage of air and gasoline, a transverse rotary tube in said chamber having at its upper portion a series of discharge outlets, a source of gasoline supply connected with said tube, a valve for controlling the passage through said chamber and connected with said tube for simultaneous operation therewith, and means for operating said tube and valve.
21. In a carbureter, the combination comprising an air inlet and a mixture outlet, a combined valve and fuel receptacle pivotally mounted in said housing and having a maximum external cross-sectional area approximately co-extensive with the corresponding cross-sectional area of said housing, said combined valve and receptacle being adapted when rotated to admit a graduated supply of air between its outer surface and the inner surface of said housing and the said receptacle being provided with one or more outlets extending through its wall, adapted to permit the escape of fuel from said receptacle and into said housing.
22. In a carbureter, the combination comprising a housing, provided with air inlet and mixture outlet openings, a combined valve and fuel receptacle pivotally mounted intermediate said openings and adapted to substantially seal communication therebetween when in a normal position, said receptacle being provided with outlets which extend through the wall thereof, and means for optionally depressing or elevating said orifices with respect to the level of the fuel

within the said receptacle whereby the fuel may be fed from said receptacle in accordance with the requirements of the engine.

23. In a carbureter having an air passage 5 through which air flows in developing explosive mixture, an air valve member disposed across said air passage in throttling relation thereto, said air valve member being rotatable at will and constructed to 10 selectively graduate the opening of the air passage by its rotation; and a reservoir having connection with the air valve member which enforces rotation of the reservoir simultaneously with the air valve member; 15 said reservoir having a series of fuel outlets progressively rendered effective by the rotation of the reservoir.
24. In a carbureter having an air passage 20 through which air flows in developing an explosive mixture, a fuel reservoir having a plurality of discharge openings adapted to be subjected to the influence of suction within the carbureter, whereby the discharge capacity of the reservoir may be varied, and 25 an air valve member in throttling relation to the air passage and in controlling relation to the fuel discharge; said air valve member being rotatable at will and constructed to

selectively graduate the capacity of the air passage by its rotation and by its said rotation also enforcing graduation of fuel discharge.

25. A carbureter having a chamber for the passage of air and explosive mixture and a combined rotary fuel feed receptacle and 30 air valve rotatable on a substantially horizontal axis and effecting the variation of both fuel and air passing through said chamber, and means for rotating said valve.

26. A carbureter having a chamber for 40 the passage of air and explosive mixture and a combined rotary fuel receptacle and air valve effecting the variation of both fuel and air passing through said chamber, said receptacle having fuel discharge means in its 45 wall adapted to vary its position relatively to the axis of rotation of said receptacle for varying the amount of fuel discharged from said receptacle.

Signed at New York city, in the county 50 of New York and State of New York, this 20th day of May A. D. 1909.

ELMER S. SMITH.
